UNITED STATES PATENT OFFICE

148,384

DESIGN FOR A CHATELAINE PIN

Sidney Packales, New York, N. Y.

Application February 18, 1947, Serial No. 136,975

Term of patent 3½ years

(Cl. D45—19)

To all whom it may concern:

Be it known that I, Sidney Packales, a citizen of the United States of America, residing in New York, county of New York and State of New York, have invented a new, original, and ornamental Design for a Chatelaine Pin, of which the following is a specification, reference being had to the accompanying drawing, forming part thereof.

Fig. 1 is a plan view of a chatelaine pin, showing my new design.

Fig. 2 is an edge view thereof.

I claim:

The ornamental design for a chatelaine pin, substantially as shown.

SIDNEY PACKALES.
